CLAIM

I claim the ornamental design for a low visibility aerodynamic antenna housing, as shown and described herein.

DESCRIPTION

This patent application is related to the following patent applications and/or issued patents:

U.S. Design patent application Ser. No. 29/232,876 filed Jun. 25, 2005 for Low Visibility Aerodynamic Antenna Housing which issued as U.S. Pat. No. Des. 531,996 on Nov. 14, 2006;

U.S. Design patent application Ser. No. 29/234,763 filed Jul. 22, 2005 for Low Visibility Aerodynamic Antenna Housing;

U.S. Design patent application Ser. No. 29/234,762 filed Jul. 22, 2005 for Low Visibility Aerodynamic Antenna Housing;

U.S. Design patent application Ser. No. 29/268,857 filed Nov. 14, 2006 for Low Visibility Aerodynamic Antenna Housing; and

U.S. Design patent application filed Ser. No. 29/272,738 contemporaneously with the present application for Low Visibility Aerodynamic Antenna Housing.

All of the foregoing applications are incorporated herein by this reference thereto.

FIG. 1 is a front perspective view of a low visibility aerodynamic antenna housing showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The broken line portions of the disclosure are for illustrative purposes only and form no part of the claimed design.
